UNITED STATES PATENT OFFICE.

EDWARD A. RIX, OF SAN FRANCISCO, CALIFORNIA.

LUBRICATING DEVICE.

SPECIFICATION forming part of Letters Patent No. 768,820, dated August 30, 1904.

Application filed December 18, 1903. Serial No. 185,618. (No model.)

To all whom it may concern:

Be it known that I, EDWARD A. RIX, a citizen of the United States, residing in the city and county of San Francisco and State of California, have invented new and useful Improvements in Lubricating Devices, of which the following is a specification.

My invention relates to improvements in lubricating machinery and the like.

My invention comprises details of construction, which will be more fully explained by reference to the accompanying drawings, in which—

Figure 1 is a longitudinal vertical section of my device. Fig. 2 is a perspective view of a capsule.

In motors driven by steam and air, and especially by the latter, large quantities of moisture are carried by the gases into the cylinder and valve and other mechanism. This moisture condensing washes away a great portion of the oil which is ordinarily used to lubricate such machines, and this is particularly the case with rock-drills, so that undue wear and cutting soon take place to the great detriment of the machinery. It is therefore necessary for the best preservation of the delicate machinery to introduce into such machines a lubricant which has sufficient body to adhere to the various parts and which will not be washed away by water. Grease is the only thing proper for this purpose. It is a difficult matter to introduce grease by means of such lubricators as are ordinarily fitted upon machines, and in the transfer of grease as ordinarily put up into a lubricator much dirt and dust are liable to be carried in with it. In drills which are lubricated by the use of oil a great deal of dirt is also carried into the drill mechanism, so much so that the principal wear arises from this dirt. An ordinary lubricator will not stand upon the rock-drill, but will break. Therefore the employees will use a can and inject oil into the air-hose of a drill before they connect the hose with a machine, and when the air is turned on it is trusted to blow the oil into the drill; but the end of the hose is often dragged about in the dirt previous to the introduction of the oil, and when the connection has been made the

dirt will be carried through the mouth of the hose and into the drill.

My invention enables me to measure the quantity to be applied and avoids carrying oil-cans into mines. Further, I am enabled to furnish a sufficiently pure product without danger of subsequent adulteration.

A represents a capsule or package of any suitable or desired size and material adapted to contain a definite or measured charge of grease. This package is preferably made independent and sufficiently expansible, so that when placed in a receiver, as will be hereinafter described, its edges will be forced outward by any internal pressure, and thus form a sufficiently tight joint with the interior of the receiver. These packages A are charged with a grease of good quality, and upon the top of the grease may be placed a disk 2 having a smaller diameter than the interior of the package. An exterior cover 3 completes the package, and these packages are made up in any quantities ready for sale and use. In order to properly apply the grease in these packages, I have shown a receiver 4, which may be of any suitable form or shape corresponding with the shape of the packages. In the present case I have shown these packages as in the form of short cylinders, and the receiver 4 is of similar shape, having an interior diameter just sufficient to admit one of the capsules or packages after its cover has been removed, the capsule being inserted with its mouth toward the bottom of the receiver. The bottom of this receiver has an annular channel made around it, as shown at 5, and this channel communicates with the part to be lubricated.

As shown in the present case, I have especially designed the device for application to drills operated by air under pressure. The air-conducting pipe or hose is connected with the receiver below the bottom, and the annular channel opens directly into the space through which the air passes to the drill, so that as the grease is forced into this passage the air will blow it into the drill and automatically apply it to all parts needing lubricating and without mixture of any dirt. In order to deliver the grease into this part of

the device as required, a movable plunger 6 may be employed. For convenience I have shown this plunger as being screw-threaded, so that by a turn or partial turn of the screw 5 the capsule or package containing the grease will be slightly compressed, and the follower 2, resting upon the bottom of the receiver and having an annular passage between it and the sides of the package substantially coincident with the channel around the bottom of 10 the receiver, it will be seen that the gradual emptying of the package will allow the grease to be forced through the annular channel and into the air-passage. The flexibility and 15 expansibility of the sides of the package or capsule are such that if there is any air, steam, or other pressure from within it will act to force these sides out against the interior of the receiver and will thus form a comparatively tight joint in the same manner as is effected by what is known as "cup-packings."

By this construction there will be no waste or danger of introducing dirt, as would be the case if the lubricant were taken from a 25 large package and placed in the grease-cup. The quantities used can be known by reason of the number of packages furnished, and waste or loss can be checked. The grease can also be gradually introduced to the part to 30 be lubricated by occasional turns of the screw plunger, and when the charge has been exhausted it is only necessary to remove the screw and the emptied package, with its follower, and to introduce a fresh one.

35 Having thus described my invention, what I claim, and desire to secure by Letters Patent, is—

1. A lubricating device comprising the combination with a receiver having a passage leading 40 to the parts to be lubricated, of a grease-container fitting the receiver and having a circumferential outlet through which the grease is delivered in the form of a thin stream, and a pressure device for ejecting the grease from 45 the container.

2. A lubricating device comprising the combination with a receiver having a passage leading to the parts to be lubricated, of a grease container fitting said passage and containing a disk whose diameter is sufficiently less than the inner diameter of the container to form a circumscribing space through which the grease is ejected in the form of a hollow column, and a pressure means for ejecting the grease from the container.

3. The combination with a receiver having a passage leading to the parts to be lubricated and having an internal support, of a grease containing capsule inverted in the receiver and having its open end resting on the support said support having a diameter sufficiently less than the inner diameter of the capsule to form a circumscribing space through which the grease is ejected in the form of a hollow column, and a follower engaging in opposition to the support for ejecting the grease through said space.

4. The combination with a receiver having a passage leading to the parts to be lubricated of a capsule containing a definite charge of grease and of such diameter that it substantially closely fits the receiver, said capsule open at one side and inserted in the receiver with the open side downward, and a disk situated at the open side of the capsule having a diameter sufficiently less than that of the former whereby a circumscribing space is provided for the ejection of the grease in the form of a hollow column, and a second follower engaging the capsule to progressively eject the grease, and provided with means for the engagement of a tool.

In testimony whereof I have hereunto set my hand in presence of two subscribing witnesses.
